UNITED STATES PATENT OFFICE.

ERNEST C. WHITE, OF EVANSTON, ILLINOIS, ASSIGNOR OF ONE-HALF TO CHARLES AMIGUET, OF NEW YORK, N. Y.

LIGHTING-FIXTURE.

1,168,839.

Specification of Letters Patent. Patented Jan. 18, 1916.

Application filed March 31, 1915. Serial No. 18,221.

To all whom it may concern:

Be it known that I, ERNEST C. WHITE, a citizen of the United States, and a resident of Evanston, Illinois, have invented certain 5 new and useful Improvements in Lighting-Fixtures, of which the following is a specification, reference being had to the accompanying drawings, forming a part hereof.

The art of interior artificial lighting has 10 now become divided into three recognized systems; direct lighting, in which the rays pass directly from the luminous point to the object; indirect lighting, in which the object is illuminated wholly by reflected 15 rays; and semi-indirect lighting, in which the object is illuminated partially by reflected rays and partially by rays passing directly from the luminous point to it. In accordance with modern practice, one of 20 these three systems is elected and fixtures so constructed as to cause illumination in accordance with the desired system, are installed. Where the degree of illumination required changes under varying uses of the 25 chamber to be lighted, either throughout the interior or at some part thereof, or where it is desired to change the character of the illumination of the chamber at different times, it is necessary, under prevailing practices, to install in the chamber separate fixtures adapted to give illumination in accordance with the systems briefly defined above, 30 these fixtures being brought into use either singly or in combination with each other as desired. Obviously, this practice is unduly 35 expensive, not only with respect to the initial cost of the fixtures but also in the consumption of lighting power, and is ill adapted for the securing of the best lighting 40 effects by the designer.

The present invention has for its object to provide a lighting fixture which shall lend itself to use in accordance with any one of the three systems referred to above, 45 or some combination of these systems.

A further object of the invention is to provide a fixture of the character described which shall be ornamental, simple in construction, inexpensive to manufacture and 50 susceptible of ready manipulation for its conversion to use in accordance with one or another of the three lighting systems.

In the accompanying drawings there have 55 been illustrated several different embodiments of the invention in order that the

broad scope thereof may be appreciated and the latitude in the matter of details of construction contemplated by the appended claims, seen. In accordance with the invention, an opaque reflector is so mounted with 30 respect to the light and is so constructed, that the rays of the light may be permitted to fall directly on the object, may pass to the object wholly by reflection, or may pass to the object partly by reflection and partly 35 through direct travel thereto, in accordance with special manipulation of the reflector or its associated parts. In one convenient form, the reflector of the improved fixture is made invertible, so that when supported 40 in a depending position, the light sheds its rays directly on the object, while when supported in inverted position, the rays of light are thrown upward to the walls or ceiling and so reflected to the object. In this embodiment, the reflector may be provided with 45 detachable means whereby a portion of the light may be permitted to pass directly to the object even when the reflector is in inverted position, thereby combining an element of direct lighting with indirect lighting. This same effect may be secured in 50 other embodiments of the invention, even where the reflector is not invertible. In such other embodiments, the fixed reflector 55 by which indirect lighting is secured, may have associated therewith suitable devices operable to permit part of the rays to pass directly to the object.

Other objects of the invention will appear 60 as this description proceeds and other advantageous features of the improved fixture will be pointed out hereinafter, reference now being had to the accompanying drawings for a detailed description of the invention, in which—

Figure 1 is a view, partly in section and partly in elevation, of a fixture embodying the invention, the reflector being indicated in depending position by dotted lines. Fig. 2 is a fragmentary detail view on a somewhat larger scale of a portion of the improved reflector, showing the form of slot 70 therein for coöperation with the supporting devices. Fig. 3 is a detail view of one form 75 of supporting device for the improved reflector, a fragment of the reflector being shown in section. Fig. 4 is a view similar to Fig. 3 but indicating the reflector as in inverted position. Fig. 5 is a sectional view, 80

taken on the plane indicated by the line 5—5 of Fig. 1 and looking in the direction of the arrows, and showing the detachable cap by which an element of direct lighting may be secured. Fig. 6 is a view in section of a slightly modified form of reflector, on which is carried a cap to embrace snugly the support for the light and prevent the upward passage of the rays. Fig. 7 is a view, partly 0 in elevation and partly in section, of a different embodiment of the invention, in which the reflector is mounted permanently in inverted position. Fig. 8 is a fragmentary view in detail taken through a portion of the 15 reflector of Fig. 7 and the cap carried thereby, and showing one means for supporting the cap detachably on the reflector. Fig. 9 is a view similar to Fig. 7 of still another form of fixture embodying the invention. Fig. 10 20 is a fragmentary view in detail of a portion of the devices shown in Fig. 9 for controlling the passage of light through the reflector.

In this specification the term "object" is 25 used to refer particularly to a limited zone or area to be illuminated and which may be supposed to be occupied by a desk, table or other thing, and the rays referred to are assumed, for convenience, to emanate from 30 an electric light, although it is evident that any other source of light may be used. The fixture, indicated generally at *a*, may carry a fitting *a'* from which extend supporting arms *a''* for the opaque reflector *b*, one or 35 more of these arms being movable laterally as through spring hinges *a''*, or otherwise, to permit their engagement or disengagement with the reflector. On the fixture *a* is also carried a lamp socket *a''* in which is fitted 40 the source of light *c*. In supporting the reflector *b* from the arms *a''*, a very simple construction has been employed in that the reflector has been slotted, as at *b'*, at points opposite the ends of the arms *a''* and these 45 arms have been formed at their ends with hooks *a''* adapted to enter the slots *b'* respectively, the noses of the hooks engaging the inner surface of the reflector *b* and retaining the reflector in place until the hooks 50 are withdrawn by especial manipulation of the arms *a''* in a manner which will be obvious. It is important to note that the supporting devices disclosed, while merely illustrative of one way of supporting the reflector *b*, possess the advantage of being 55 simple in construction, and are of such character as to insure practically a light-proof closure at the point of engagement of the hooks *a''* with the slots *b'*. This closure is 60 effected by making the slots *b'* of substantially the width of the arms *a''* and by forming the ends of the arms with shoulders *a''*, one or both of which engage the outer surface of the reflector *b* and prevent the filtering of light therethrough, as appears

clearly from Figs. 3 and 4. Again, this method of supporting the reflector *b* has the virtue that the reflector can be inverted as indicated in Fig. 1, and the same co-operation between the slots *b'* and the noses *a''* effected when the reflector is in this inverted position. Accordingly, by a very simple manipulation of the arms *a''*, one may invert the reflector *b* and transform the lighting fixture from one of the indirect 75 lighting type to one of the direct lighting type, as will appear hereinafter. One end of the reflector *b* may have a shouldered flange *b''* stamped therein on the outer periphery of which may be fixed laterally extending pins *b'''* adapted to pass through notches *d* cut in the inner edge of a reversely bent lip *d'* struck up on a cap *d''* which is of opaque material and may present an ornamental exterior surface. On the shoulder 80 *b''* of the reflector *b* may rest a glass plate *e*, accidental movement of which may be prevented positively by means of swiveled clips *f* fixed on the inner surface of the reflector *b* in operative relation to the plate. 90

It is to be understood that this invention is not to be limited to the cross-sectional shape of the reflector *b* or that of any of the other elements described, although it will be clear that the general contour of the cap *d''* and 95 of the plate *e* must conform with that of the flange *b''* or the equivalent finish of the opening in the reflector *b*. Again, the devices by which the cap *d''* and the plate *e* are detachably held in place on the reflector *b* may be changed through wide ranges, the invention not being limited to any such details.

In use it may be supposed that the improved form of fixture shown in Fig. 1 has 105 the reflector *b* mounted in inverted position with the opaque cap *d''* held in light-proof engagement with the reflector as through the engagement of the pin *b'''* with the lip *d'* of the cap, it being understood that the cap 110 is placed in position by passing the pins through the notches *d* and then rotating the cap. When in this position the reflector *b* throws all of the light to the ceiling and the objects are illuminated in accordance with the indirect lighting system. If now, it is desired that an element of direct lighting 115 shall be included with this indirect lighting, as where an object under the fixture needs to have a more intense light thrown on it, the cap *d''* may be readily detached from the reflector *b* in the way described, and the direct rays of the light *c* permitted to pass downward through the glass plate *e*. Whether this plate *e* is to be translucent or 120 transparent will depend upon conditions, the invention including in its scope the use of interchangeable transparent and translucent plates and the entire omission of the plate. If conditions make it desirable to 125

130

focus most of the light on objects below the fixture, to the partial exclusion of the more general illumination of the entire chamber by the indirect method, the reflector b is inverted so as to assume the position indicated in dotted lines in Fig. 1, the cap d^2 and plate e (where used), of course, being removed before inversion. When the reflector is in the position now under consideration, most of the light will be thrown downward and direct illumination of the object effected, although where the diameter of the opening in the top of the reflector is greater than the diameter of the light c , rays of light will pass upward and illuminate the ceiling, thereby introducing an element of indirect lighting. From the description thus far given, it will be appreciated that the supporting devices for the reflector b should be so disposed with respect thereto that the reflecting properties of the reflector will be unimpaired whether the reflector be in a depending position or in inverted position. For instance, as shown in Fig. 1, the slots b' which the ends of the arms a^2 engage, are formed at about the mid-section of the reflector b , this reflector being of substantially conical form and the reflecting surfaces thereof being properly disposed with respect to the light c whether the reflector be in one position or another.

The reflector b shown in Fig. 6 differs only from that shown in Fig. 1 in that it is provided with a cap D which, while substantially of the same character as the cap d^2 is formed with a central opening D' adapted to engage snugly some portion of the light c or its socket a^4 when the reflector is supported in depending position, thereby preventing any rays of light from passing upward and eliminating the element of indirect lighting referred to in connection with the description of Fig. 1. When the reflector b is mounted in inverted position (that shown in full lines in Fig. 1), the cap D shown in Fig. 6 may be employed where an element of direct lighting through the opening D' is wanted, or this cap may have interchanged therefor the cap d^2 shown in Fig. 1.

Reference is now to be had to the somewhat modified type of improved fixture illustrated in the embodiments shown in Figs. 7 and 9. In these embodiments the reflectors are not invertible, but are intended to remain in position for indirect lighting, provision being made in each instance for an element of direct lighting, either outright or to a somewhat modified degree. In Fig. 7, the reflector g is supported by suitable arms h attached to the fixture A , and may be provided at its lower edge with a shouldered flange g' on the outer periphery of which may be fixed laterally extending pins g^2 for engagement with key-hole slots i in lugs k secured to a bottom cap l of opaque material and preferably of ornamental appearance. The cap l is suspended from the reflector g by engaging the enlarged portions of the key-hole slots i with the pins g^2 and then rotating the cap with respect to the pins, in a manner which will be obvious. The cap l , it will be observed, is preferably of similar form to the reflector g and has its mouth of greater diameter than the diameter of the bottom of the reflector so that a space is left between the cap and the outer walls of the reflector for the passage of light. By this construction, when the cap is in the position illustrated in Fig. 7, indirect lighting will be effected and, in addition, the rays of light which pass through the opening in the bottom of the reflector g , and through the glass plate m (which may be employed, if desired, as pointed out with respect to the other embodiments of the invention), will be reflected from the inner surface of the cap l through the space between the cap and the walls of the reflector g and thrown over the surface of the reflector, thereby illuminating the same highly. The illumination thus secured by the reflected light on the outer surface of the reflector may be termed a somewhat modified form of direct lighting. However, if desired, the rays from the light c may be permitted to pass directly to the object, by removing the cap l . The intensity of this direct lighting can be further controlled by using the glass plate m and by making it either transparent or translucent as required.

The embodiment shown in Fig. 9 resembles, in principle of operation, that shown in Fig. 7. In this embodiment, the reflector n is imperforate, so far as regards the escape of light through the walls thereof, except for a row of openings n' arranged in substantially the same horizontal plane and preferably adjacent the upper edge of the reflector. Fitting rather snugly within the reflector n , and in proximity to the row of openings therein, is supported a ring o in which is formed a series of openings o' corresponding to the openings n' in the reflector n and adapted to be brought, respectively, into registry with these last named openings to permit the passage of light through the wall of the reflector, or to be moved out of registry therewith to blank the holes and prevent the escape of light. This ring o , which will find many mechanical equivalents, may be supported conveniently in position on a spider, the arms of which o^2 conform in outline to the contour of the reflector and are secured at their lower edges to a rotatable spindle o^3 which passes through the reflector n , and is preferably co-axial with the reflector, and is provided on the outer side of the reflector with a knob o^4 to facilitate oscillation of the spider and

the ring o . The reflector n may be supported conveniently by arms p which may be arranged to pass through slots o^5 formed in the ring o , these slots being of such length 5 as to limit the rotative movement of the ring in each instance to a degree necessary to insure registration of the holes n' and o' in one extreme position and blanking of the holes n' in the other extreme position. With 10 the reflector n , or supported thereon, is a reflecting rim g , the reflecting surface of which is so disposed with respect to the openings n' as to receive the direct rays of light therefrom when these holes are open 15 and reflect these rays downwardly and reversely against the outer surface of the reflector n so as to illuminate the same highly. In this way an element of direct lighting is obtained to a modified degree, with the indirect 20 lighting insured by the opaque reflector n , as pointed out with respect to the illuminated surface of the reflector g in Fig. 7. By manual manipulation of the ring o through the exposed knob o^4 the holes n' 25 can be blanked and the fixture converted into one of the indirect lighting type.

As has been emphasized throughout this specification, the several fixtures disclosed are intended to be merely illustrative of the 30 different types or embodiments of this invention, the gist of which resides in the provision of a fixture equipped with devices for converting it into one intended to afford illumination in accordance with any one of the systems briefly referred to in the preamble or in accordance with varying combinations of these systems as appears from the specific description. It is also important to 35 state that where reference has been made to the use of an invertible opaque reflector, a translucent one may be substituted and the effects of a semi-indirect lighting system thereby secured. Re-arrangements of the 40 parts and modifications in the details of structure will suggest themselves to those skilled in the art, but all such departures from the preferred embodiments are to be deemed within the spirit of this invention 45 provided they fall within the scope of the appended claims.

I claim as my invention:

1. In combination with a source of light, a lighting fixture having an opaque reflector, means to support the reflector in inverted position to throw rays of light upward, said reflector having an opening formed in its bottom to give a useful element of direct downward lighting and a flat translucent plate mounted in the opening. 55
2. In combination with a source of light, a lighting fixture having an opaque reflector, means to support the reflector in inverted position to throw rays of light upward, said reflector having an opening 60 formed in its bottom to give a useful ele-

ment of direct downward lighting, a flat translucent plate mounted in the opening, and removable opaque devices normally covering the opening.

3. In combination with a fixed source of light, an invertible reflector and relatively fixed supporting arms to engage the reflector in inverted position or, at the same points of engagement, in depending position to support the reflector in inverted position in 75 desired focal relation to the light or in depending position in substantially the same focal relation, respectively.

4. In combination with a fixed source of light, an invertible reflector, relatively fixed 80 supporting arms for the reflector and means to engage the supporting arms with the reflector in inverted position to support the reflector in inverted position in desired focal relation to the light, said arms being engageable with the reflector at the same points of engagement in depending position to support the reflector in depending position in 85 substantially the same focal relation to the light and said reflector being invertible 90 without disturbing the fixed source of light or the supporting arms.

5. In combination with a fixed source of light, an invertible reflector provided with an opening in its bottom, relatively fixed 95 supporting arms to engage the reflector in inverted position, or at the same points of engagement in depending position, to support the reflector in inverted position in desired focal relation to the light or in depending 100 position substantially in the same focal relation, respectively, an opaque cap to close the opening and cut off the element of direct lighting when the reflector is in inverted position, and means to support the cap detachably on the reflector.

6. In combination with a source of light, a lighting fixture having arms and a reflector provided with slots to receive the ends 110 of said arms to support the reflector, said arms and slots being so formed and disposed with respect to each other as to permit the reflector to be inverted and maintain its proper reflecting position with respect to the source of light. 115

7. In combination with a source of light, a lighting fixture having spring arms secured thereto, and an opaque reflector provided with slots through which the ends of 120 said arms pass respectively to support the reflector, said arms and slots being so formed and disposed with respect to each other as to permit the reflector to be inverted and maintain its proper reflecting position with respect to the source of light. 125

8. In combination with a source of light, a lighting fixture having spring arms, an opaque reflector provided with slots adapted to receive the ends of said arms respectively for the support of the reflector said reflector 130

tor being formed in its bottom with a flanged opening, laterally extending pins carried on said flange, an opaque cap formed with a reversely bent lip slotted on its inner 5 periphery to permit the engagement or disengagement of the cap with the pins over the opening, whereby the cap can be removed to give an element of direct lighting when the reflector is supported in its inverted position and permit the reflector to

be supported in a depending position for direct lighting by passing the source of light through the opening.

This specification signed and witnessed this 30th day of March, A. D. 1915.
